UNITED STATES PATENT OFFICE

CHARLES BREWSTER, OF MONTREAL, QUEBEC, CANADA.

SKATE ATTACHMENT.

SPECIFICATION forming part of Letters Patent No. 236,668, dated January 18, 1881.

Application filed November 17, 1880. (No model.)

To all whom it may concern:

Be it known that I, CHARLES BREWSTER, of the city and district of Montreal, Province of Quebec, Canada, have invented certain new and useful Improvements in Skate Attachments; and I do hereby declare the following is a full, clear, and exact description of the same.

This invention has reference to further improvements in skate attachments, to cause in some respect a more desirable action of the parts forming the attachment, and in another or in others a cheaper form of construction.

In the drawings hereunto annexed similar letters of reference indicate like parts, and Figure 1 is a side elevation of a skate embodying my invention. Fig. 2 is a plan of front end of skate right side up. Fig. 3 is a plan of front end of skate upside down, with runner removed. Fig. 4 is a plan of heel end of skate right side up. Fig. 5 is a plan of heel end of skate upside down. Fig. 6 is a side elevation of a modification of the fastenings. Fig. 7 is a side elevation of Fig. 6. Fig. 1 is shown on a somewhat smaller scale than the other figures, which are about full size for an adult.

Letter A is the runner of the skate, provided with three projections, B, C, and D, for attaching the plates to, the front plate being attached to C and D by brackets E and F, one side of each bracket being riveted to the runner and the other to the sole-plate A'. The brackets E are furthermore arranged to form guides to a T-shaped slide, G, as will be clearly understood from Figs. 1 and 3. This slide has its front edge, H, turned up at right angles, and portions I of the under side of the top bar of the T also turned up at right angles, whereby said top bar is converted into a groove for holding and guiding the shanks of the clamps K.

L is a slot cut in the body of G for the projections C to pass through, and of sufficient length to allow G to have all the necessary motion.

In the shank of each of the clamps K a stud, M, having a button-head, is secured. The body of this stud comfortably fills the inclined slots N in the sole-plate on the one side of the shank of the clamps, and the transverse slots O, cut in G on the other side. Its extremity is pro-

vided with a washer, P, over which the end of M is riveted, thus forming a button or flange head on the under side.

R is a standard riveted into the T-slide G, having a screwed hole in it to agree with the screwed spindle B². The sole-plate is provided with a depressed portion, C², so that the button-heads of M shall not stand up above the remaining portions of the surface of the sole-plate, and thus prevent the sole of the boot from resting fairly upon them. It will therefore be seen that as the T-shaped slide G is moved backward and forward the clamps K are caused, by the action of the studs M, to be drawn in and pushed out to gripe or release the sole of the boot placed upon the plate A'. Furthermore, it will be seen that as the slide G is moved toward the heel they (the clamps) move inward to gripe the boot, which is an important improvement, for it must be remembered that the front part of the boot from the tip of the toe is tapered for a considerable distance, becoming larger as it approaches the heel, so that by thus taking advantage of the form of the boot a larger range of size of boot for the same skate is provided for, as well as causing the fastening and unfastening of the clamps to be more quickly accomplished.

The projection B is provided with a recess at D² for the reception of a plate, E², (the section of B shown in Fig. 5 is on line x, Fig. 1,) which is simply cut to fit and then put in place in the recess. The heel-plate I² is provided with openings to fit corresponding projections, F², formed on B, and these projections are entered into the opening in the heel-plate and riveted over, when the whole is secured together, the plate E² forming a guide and the riveting an attachment, the whole forming a much cheaper and better guide than any of those at present in use for the heel-clamp slide K².

It will be seen that the stationary and front clamps, L², for the heel are made in one with the plate I², while the clamps M², for gripping the rear of the heel, are made in one with the slide K².

N² is a standard riveted to the slide K², and forms a bearing to receive the journals and

collared end of the spindle B² to revolve in. (See Fig. 5.)

The slide K² is so clearly shown in the drawings that no further description of it is considered necessary.

On the spindle B² a windlass-head is secured, by which, with the finger and thumb, the spindle is rotated.

In the modification shown in Figs. 6 and 7
 10 my invention is arranged to apply to gripping the front part of the boot only, as some persons object to have the heels of their boots, such as ladies' fine boots, cut by the heel-clamps M². It will therefore be understood that the
 15 sole-clamps shown in these two figures (6 and 7) may be used with almost any of the heel-clamps in use that hold the heel independent of the sole. In this case the parts marked with the same letters of reference are the same
 20 as those already described, only as follows: The T-plate G is cut shorter and the sole-plate A' made to extend back farther, and in it is secured a standard, S², which corresponds in construction with that, N², already described.
 25 The spindle B² in this case is made short, as shown, but similarly operated by a capstan-head, S.

Instead of the brackets E shown in Figs. 1 and 3, two plates, E², are provided, set in a
 30 recess, D², in projection C, in a similar manner to the plate E², which has hereinbefore been described to be placed in the recess D² in pro-

jection B, and the rear end of the plate A' is attached to C in the same manner that the plate I² has been hereinbefore described to be 35 secured to projection B. Thus it will be seen that the two plates E² form a perfect and cheaply-formed guide for the slotted shank of the plate G.

What I claim, and wish to secure by Letters Patent, is as follows:

1. The combination of the plate A', having inclined slots N, slide G, having slots O, and clamps K, having studs M, with an operating device, B², substantially as set forth. 45

2. The combination of the spindle B², having windlass-head S, with slide G, constructed and arranged as described, to operate in conjunction with plate A' and clamps K, constructed and arranged as described, and with 50 slide K², also constructed and arranged as described, the whole substantially as set forth.

3. The combination of the projection B, having recess D², plate E², heel-plate I², and slide K², substantially as and for the purposes set 55 forth.

4. The combination of the projection C, having recess D², plates E², and slide G, substantially as and for the purposes set forth.

C. BREWSTER.
